UNITED STATES PATENT OFFICE.

KENDEL J. TERRELL, OF HUSHPUCKENA, MISSISSIPPI.

ENTRANCE AND EXIT CAR FOR TRAINS.

1,337,492.

Specification of Letters Patent. Patented Apr. 20, 1920.

Application filed August 30, 1919. Serial No. 320,832.

To all whom it may concern:

Be it known that I, KENDEL J. TERRELL, a citizen of the United States, residing at Hushpuckena, in the county of Bolivar, State of Mississippi, have invented certain new and useful Improvements in Entrance and Exit Cars for Trains; and I do hereby declare the following to be a full, clear, and exact description of the invention, such as will enable others skilled in the art to which it appertains to make and use the same.

This invention relates to the class of railway rolling stock and more particularly to an improved entrance and exit car designed to facilitate taking on and letting off of passengers at stops or stations and also to facilitate the collection of fares, while at the same time giving greater convenience to the passengers without the necessity of being jostled about by passengers entering and leaving the car at the same time by means of the same doorway and steps.

A further object of the invention is to provide an entrance and exit car which will serve as a feeder for or in conjunction with a railway passenger train drawn by a locomotive or electric power and comprising a series of passenger cars to and from which entrance and exit are made by passing through a car embodying the subject matter of the present invention and which is so arranged that the passengers entering the car will pass through one doorway and those making exit will pass through a separate doorway, the car also being provided with sufficient seats to accommodate a goodly portion of the passengers desiring to make exit at the next stop or station, while the conductor is positioned at one end of the car so that passengers who had boarded the train through this feeder car will pay their fares as they pass into the regular passenger cars with proper seating capacity for the continuance of a particular journey with comfort, thereby also obviating the necessity of the conductor passing through the cars in order to collect fares, as is now generally done.

With the above objects and others in view as will appear as the specification proceeds, the invention comprises certain novel combinations and arrangements of parts as will be hereinafter more particularly pointed out and claimed.

Reference is had to the accompanying drawings forming a part of this applica-

tion, wherein like characters designate corresponding parts throughout the several views, in which—

Figure 1 is a horizontal sectional view of a car constructed in accordance with the invention,

Fig. 2 is a vertical transverse sectional view, and

Fig. 3 is a vertical longitudinal sectional view.

Referring to the drawings in detail, the numeral 10 designates the body of the car having the usual flooring portion 11 and roof 12, while provided at the ends of the car are the end walls 13 through which door openings 14 are made preferably controlled by oppositely sliding doors 15 affording free entrance and exit to and from passenger cars of usual seating capacity, coupled to one or both ends of the entrance and exit car constituting the subject matter of the present invention.

The car is made preferably slightly shorter than the standard passenger car, say 30 feet instead of 32 and the intermediate portion indicated at 16, preferably a distance of about 14 feet, constitutes a lobby or waiting portion which may be provided with a series of seats 17 extending lengthwise, transversely or otherwise. At either side of the intermediate portion 16 are arranged sliding doors 18 supported for movement toward each other at the intermediate or central portion of the car as by means of a suitable hanger 19 as commonly used for slidably supporting side doors or of any preferred form.

The doors 18 move toward a stop or limiting member 20 and these doors are preferably about seven feet wide and overlap when in closed position, the side of the car at each side of the doorway, about six inches so as to give security against displacement or resultant accidents, but are accommodated by the intermediate portion, against the sides of the car and concealed in the usual or any preferred manner as well as operated by any suitable means common in the art. From each of these doors lead steps 21 by means of which entrance and exit to and from the car is made possible.

There is thus provided at each end of the car beyond the doors 18 when in closed positions, a space or compartment 22 divided by a transverse partition or railing 23 from the intermediate portion of the

car so as to accommodate the conductor or collector, it being understood that when the passenger cars are coupled to one end of the present car, one of the end doors 15 5 will be closed and the conductor or collector will occupy the compartment which controls the entrance and exit to the regular passenger or seating cars, the present car being preferably positioned at one end 10 of the train. If passenger cars are coupled to either end of the present car then a conductor or collector is positioned in each compartment 22.

Each partition or railing 23 is provided 15 with a central passage way 24 communicating with and leading to the doorway 14 and is capable of being closed as by means of a bar 25 hinged at one end to swing backwardly, or otherwise arranged so that the 20 entrance and exit of passengers can be controlled.

Thus in the use of the car of the present invention, the passengers enter one of the doors 18 to the exclusion of the other and in 25 passing into the regular passenger or seating cars, will pass the conductor or collector who will thus be able to collect the fares with facility and be notified as to the condition of all boarding a train and 30 any particular stops to be made. These passengers will be permitted to pass into the other cars without obstruction, since the aisles and doorways will have been previously cleared by those desiring to make exit 35 passing into the present car prior to the approach to a stop or station. The door 18 adjacent to the end at which the conductor is disposed, is preferably used to accommodate those passengers boarding the 40 car and train until they have passed through into the other cars upon the collection of their fares, or both ends may be used where cars of a train are coupled to each end of the present car. However, in the first in- 45 stance the passengers desiring to alight at a station will be accommodated by the seats 17 and the colonnade and lobby spaces pro- vided at the exit end, which in view of the 50 nature of the doors used in connection with steps of corresponding width, will permit the handling of a large number of passengers quickly entering and making exit at the same time, with considerable saving in time and confusion as often occurs in the

present mode of travel and handling of passengers, thereby rendering the device especially desirable in rush hours, particularly by local trains or on any special occasion of heavy traffic.

On excursion runs, when the train is go- 60 ing its trip at stations or stops where large numbers of passengers are to enter the train, both doors may be used for entrance and on the return trip both may be used for exit. Again, where different classes of 65 passengers ride separately, the car is preferably stationed at or near the middle of a train.

What is claimed is:—

1. An entrance and exit car for employ- 70 ment as an element of a train of cars comprising a body having a door in each end for passage to other cars of a train, and a door in each side adjacent to each end but spaced therefrom and a barrier disposed 75 between each end pair of side doors and the adjacent end of the car with a resultant conductor's compartment, between each barrier to the corresponding end of the car.

2. An entrance and exit car for employ- 80 ment as an element of a train of cars comprising a body having a door in each end for passage to other cars of a train, a door in each side adjacent to each end but spaced therefrom, a barrier disposed between each 85 end pair of side doors and the adjacent end of the car with a resultant conductor's compartment, and a series of seats at each side of the car body between the end pairs of doors.

3. An entrance and exit car for employ- 90 ment as an element of a train of cars comprising a body having a door in each end for passage to other cars of a train, a door in each side adjacent to each end but spaced 95 therefrom, a barrier disposed between each end pair of side doors and the adjacent end of the car with a resultant conductor's compartment, and a series of seats at each side of the car body between the end pairs of 100 doors, the car body between the doors of each end pair being without seats.

In testimony whereof I affix my signature in the presence of two witnesses.

KENDEL J. TERRELL.
